US00D757026S

(12) **United States Design Patent**
Lim et al.

(10) **Patent No.:** US D757,026 S
(45) **Date of Patent:** ** May 24, 2016

(54) **DIGITAL CAMERA WITH A GRAPHICAL USER INTERFACE**

(71) Applicant: **Samsung Electronics Co., Ltd.**, Suwon-Si, Gyeonggi-Do (KR)

(72) Inventors: **Eun Sil Lim**, Seoul (KR); **Hee Kyung Jeon**, Seoul (KR); **Jee-Yeon Wang**, Seoul (KR)

(73) Assignee: **Samsung Electronics Co., Ltd.**, Gyeonggi-do (KR)

(**) Term: **14 Years**

(21) Appl. No.: **29/445,325**

(22) Filed: **Feb. 11, 2013**

(30) **Foreign Application Priority Data**

Sep. 18, 2012 (KR) 30-2012-0045063

(57) **CLAIM**

We claim the ornamental design for a digital camera with a graphical user interface, as shown and described.

DESCRIPTION

The FIGURE is a front-side view of a digital camera with a graphical user interface showing our new design.

The broken lines shown in the drawing illustrate the digital camera and portions of the graphical user interface that form no part of the claimed design.
